UNITED STATES PATENT OFFICE.

JOHN C. ADAMS, OF SUPERIOR, WISCONSIN.

AUTOMOBILE-HEATER.

1,815,195.

Specification of Letters Patent. Patented Sept. 2, 1919.

Application filed December 17, 1917. Serial No. 207,456.

To all whom it may concern:

Be it known that I, JOHN C. ADAMS, a citizen of the United States, residing at Superior, in the county of Douglas and State of Wisconsin, have invented certain new and useful Improvements in Automobile-Heaters, of which the following is a specification, reference being had therein to the accompanying drawing.

10 This invention relates to heating devices for automobiles and has special reference to that type of such devices wherein the heat developed in the exhaust manifold is utilized for heating the inclosed habitable portion of the automobile.

15 While the invention herein disclosed or certain slight modifications of same may be employed in connection with various makes of automobiles it is particularly designed for 20 and forms a coöperative part of that type of automobile known as the Franklin and in which the engine has formed as a coöperative part thereof a laterally projecting shelf intermediate of the ends of the cylinders 25 and just above which the various exhaust pipes communicate with each other.

20 The principal objects of the invention are obvious and one of which in particular is as above inferred, that of producing a wall construction coöperatively adaptable to the 30 engine of the Franklin type of car.

35 The various objects will become more apparent and appreciable in the further description of the invention.

40 I am aware that it is old in the art to utilize the heat from the manifold of the engine for heating other portions of the automobile and therefore am not entitled to protection upon the broad idea.

45 In the accompanying drawings forming part of this application and in which like reference characters indicate like parts,

Figure 1 is a side elevation of the improved heater applied to a Franklin engine,

Fig. 2 is a top plan view of same,

Fig. 3 is an enlarged transverse sectional view of the heating conduit, and

Fig. 4 is a longitudinal section of the intake end of the heating conduit.

50 1 represents the cylinders of an automo-

bile engine which are, in certain types of cars, surrounded intermediate of the ends of the cylinders by a horizontally projecting reinforcing shelf, as indicated at 2, and above which rests the exhaust manifold 3, 55 each individual exhaust pipe 4 leading from its respective cylinder at a point some distance above the shelf 2.

As before stated my present invention is especially adapted to this form of engine 60 construction and to this end it has peculiar characteristics which will appear later.

The main body of the air conduit is composed of the outer wall 5, the upper portion of which is arched in the form of substantially a semi-circle forming the roof of the conduit. The shorter termination of the arched portion is bent outwardly at right angles to the body portion forming an angularly projecting flange 6. This side of 70 the conduit is the engine cylinder side and is of fabricated construction for convenience in applying it to or removing it from the engine. The lower portion of this side of the conduit comprises the angular member 75 7 which is first put into place between the manifold 3 and the cylinders of the engine and securely bolted to the upper face of the shelf 2 by suitable bolts 8 through the projecting flange thereof; and the similarly 80 shaped portion 9 which, however, is in an inverted position and securely bolted to the upstanding portion of the member 7 by through bolts 10 and the projecting flange 11 of the member 9 is bolted to the flange 6 by 85 suitable bolts 12.

The holes 13 in the conduit through which the exhaust pipes pass are formed half within the member 9 and half within the adjacent termination of the downwardly curved 90 top portion of the conduit.

By this manner of construction of the engine side of the conduit it is evident that the operation of applying the same becomes quite simple.

95 The member 7 is first slid in longitudinally between the manifold and the engine cylinders and made fast to the engine shelf 2 with the screw bolts 8, then the member 9 is put in place up against the under side 100

of the exhaust pipes 4 and attached to the member 7 by the bolts 10. The remaining portion 5 of the conduit is then put in place over the manifold and the exhaust pipes, the 5 flange 6 being securely bolted to the flange 11 by the bolts 12 and the base flange 14 of the member 5 secured to the engine shelf 2 by the bolts 15.

The rear end of the conduit is made somewhat funnel shaped as at 16, the upper wall being inclined upwardly from the body portion and the outer side wall being inclined outwardly from the body portion conforming with the shape of the shelf 2 as found 15 on the engine.

The outer terminal edges of the funnel shaped portion are turned outwardly forming flanges 17 which abut against the dash board 18 of the automobile and are secured 20 thereto by suitable bolts or screws 19.

Within the opening formed through the dash board opposite the mouth of the conduit is installed any suitable form of register indicated at 20 and which is provided 25 with a foot lever 21 for opening or closing the shutters of the register as is commonly known.

The forward end of the conduit is made flaring as at 22 for the proper reception of 30 the air currents as they enter the front portion of the engine hood and transversely positioned adjacent the bottom of the forward end and within the flaring mouth is mounted a shaft 23 which carries a plurality of wire 35 screens 24 united by suitable rivets 25. This pack of screens is of a size to snugly fit within the front end of the conduit and form a screened closure for same or it may be turned down forwardly as indicated in dotted 40 lines, Fig. 4, when the heater is not being used. It is found in practice that a plurality of screens placed together as illustrated in the drawings gives very much better results than a single screen which appears to 45 be due to the fact that the current of air passing therethrough into the conduit is more thoroughly broken up and its horizontal movement retarded thus causing the temperature to rise and the ability of the air to 50 carry the heat from the manifold greatly improved.

It is also determined that when the screen closure 24 is lowered as illustrated in the dotted lines and the register 20 opened, but 55 very little heat is carried through the conduit.

Having thus described my invention what I claim as new and desire to secure by Letters Patent, is:

60 1. The combination with an internal combustion engine having a laterally projecting exhaust pipe from each cylinder of the engine entering a horizontally disposed manifold, of a fabricated air conducting conduit

surrounding the manifold and comprising a 65 base, an upstanding downwardly curved major portion fixed to the base, a spaced minor portion fixed to the base between the manifold and the engine cylinders and a third portion overlapping and removably fixed to 70 the minor portion and also removably fixed to the major portion whereby the device may be quickly and conveniently applied to or removed from the manifold of the engine.

2. The combination with an internal combustion engine having a laterally projecting shelf thereabout, and an exhaust manifold above the shelf, of a fabricated air conducting conduit comprising an upstanding downwardly arched major portion fixed to the 75 shelf and overlapping the manifold, an upstanding spaced minor portion between the manifold and the cylinders of the engine also fixed to the shelf and an intermediary portion fixed to and uniting both of the 80 other portions, holes, half in the arched major portion and half in the intermediate portion through which the exhaust pipes of the engine extend and means for controlling the passage of air through the conduit. 85

3. The combination with an internal combustion engine on an automobile, having a horizontally disposed manifold, of a fabricated air conducting conduit communicating with a habitable portion of the vehicle, said 90 conduit surrounding the manifold and comprising a base, an upstanding downwardly curved major portion fixed to the base, a spaced minor portion fixed to the base between the manifold and the engine cylinders and a third portion overlapping and 95 removably fixed to the minor portion and also removably fixed to the major portion substantially as and for the purpose described. 100

4. The combination with an automobile having an internal combustion engine with a laterally projecting shelf below the manifold thereof and a dash board adjacent the rear of the engine, of a substantially inverted U-shaped air conduit fixed to the shelf its entire length and having a separable sectional inner wall intermediate of the manifold and the engine, said conduit having an open forward end and a substantially funnel shaped rear end attached to and discharging through a damper controlled opening in the dash board substantially as described. 115

5. The combination set forth in claim 4, with an adjustable open mesh screen at the 120 forward end of the conduit for breaking up and regulating the air passing therethrough.

6. The combination set forth in claim 4, with a closure for the forward end of the conduit comprising a plurality of open 125 meshed wire screens.

7. The combination set forth in claim 4, with a screen located within the air receiving

end of the conduit, whereby the air as it enters the conduit is broken up into a plurality of horizontally moving currents.

8. The combination set forth in claim 4, 5 with an inclosure for the forward end of the conduit, comprising a plurality of open meshed wire screens fastened together and mounted upon a shaft journaled transversely the receiving end of the conduit

whereby the closure may be pivotally adjusted to control and regulate the current of air passing through the conduit.

In testimony whereof I hereunto affix my signature in the presence of two witnesses.

JOHN C. ADAMS.
